US00D762647S

(12) **United States Design Patent**
Fitch et al.

(10) **Patent No.:** US D762,647 S
(45) **Date of Patent:** ** Aug. 2, 2016

(54) **ELECTRONIC DEVICE**

(71) Applicant: **Hand Held Products, Inc.**, Fort Mill, SC (US)

(72) Inventors: **Timothy R. Fitch**, Syracuse, NY (US); **Kirk Michael Burmeister, II**, Charlotte, NC (US); **Scott Garmon**, Waxhaw, NC (US); **Jonathan T. Grunow**, Indian Trail, NC (US)

(73) Assignee: **Hand Held Products, Inc.**, Fort Mill, SC (US)

(**) Term: **15 Years**

(21) Appl. No.: **29/528,590**

(22) Filed: **May 29, 2015**

Related U.S. Application Data

(63) Continuation of application No. 29/436,337, filed on Nov. 5, 2012, now Pat. No. Des. 730,902.

CLAIM

The ornamental design for an electronic device, as shown and described.

DESCRIPTION

FIG. 1 is a front elevation view of the electronic device; FIG. 2 is a rear elevation view of the electronic device; FIG. 3 is a left side elevation view of the electronic device; FIG. 4 is a right side elevation view of the electronic device; FIG. 5 is a bottom plan view of the electronic device; and, FIG. 6 is a top plan view of the electronic device. Broken lines and unshaded portions contained within broken lines depict portions of the electronic device that form no part of the claimed design.

1 Claim, 6 Drawing Sheets
